APPARATUS FOR CRUSH DRESSING
GRINDING WHEELS

John C. Wilson, Springfield, Ohio, assignor to The
Thompson Grinder Company, Springfield, Ohio,
a corporation of Ohio

Application September 27, 1945, Serial No. 618,814

16 Claims. (Cl. 125—11)

1

This invention relates to methods and apparatus for the dressing of grinding wheels which are especially hard such as diamond grit wheels.

The primary object of this invention is to provide a method and apparatus for the satisfactory dressing of diamond grit wheels.

Another object is to provide a method and apparatus for crush dressing diamond grit wheels.

Still another object is to provide a method and apparatus for successively transferring configurations to harder roll members until the final roll will satisfactorily crush dress a diamond grit wheel.

These and other objects and advantages become more apparent upon reference to the following specification taken together with the accompanying drawings in which:

Figure 1 is a perspective view illustrating the elements of a machine adapted for practicing the methods of this invention;

Figure 2 is a side elevation showing the wheel in a grinding position;

Figure 3 is a view similar to Figure 2 but showing the wheel being crush dressed;

Figure 4 is a section taken along the line 4—4 of Figure 1 showing the clutch employed when the wheel is driven at low speeds;

Figure 5 is a section indicated by line 5—5 on Figure 2 showing a configuration being transferred to an intermediate dressing roll, and

Figure 6 is a view taken along the line of 6—6 on Figure 3 showing the diamond grit wheel in the process of being crush dressed.

Referring to the drawings, 10 indicates the table for supporting a workpiece 12 which is to be ground by a wheel 14, the wheel and table being relatively reciprocable.

The wheel 14 is carried on a shaft 16 which is adapted for being driven at grinding speeds by a motor 18. Also connected with the shaft 16, through an overrunning clutch 20, is a motor 22 which drives into the said shaft through reduction gearing. When the motor 18 is de-energized, the motor 22 may be energized to drive the wheel 14 at reduced surface speeds. When the motor 18 is energized, the clutch at 20 disengages the motor 22 from the shaft 16 and the wheel may be driven at high surface speed.

The wheel 14, as mentioned previously, is a diamond grit wheel comprising a plurality of small particles of diamond bonded together with a vitrified or resinous bonding compound.

Also carried on the table or bed 10 in bracket 24 is a roller 26 comprising particles of silicon car-

2

bide which are preferably bonded together with a vitrified composition. While the wheel 14 having the diamond grit therein is too hard to be crush formed by a steel roller, the vitrified silicon carbide roller 26 is sufficiently hard to perform this operation. In turn, the roller 26 may be formed by bringing it into crushing engagement with a steel roller.

Such a steel roller is indicated at 28 and a means for supporting the roller 28 is shown at 30. The table 30 is slidable so as selectively to bring the roller 28 into crushing engagement with the roller 26. The roller 26 is freely mounted in its supporting bracket 24 while the roller 28 is adapted for being driven in rotation by a motor 32 through reduction gearing which gives a suitably low surface speed of the said roller.

In Figure 2 is illustrated a portion of the grinding cycle wherein the wheel 14 is grinding the workpiece 12, while the roller 28 is being urged into engagement with the roller 26. After the roller 26 has been crush formed to the desired shape, the roller 28 and its support 30 is retracted to their Figure 3 position. Thereafter, when it is desired to dress the wheel 14, it may be moved into position over the roller 26 and driven at low speed by the motor 22 while being urged against the said roller. After the wheel has been dressed, a new grinding cycle may be instituted and, if necessary, the roll 26 may again be trued by the roll 28.

A diamond grit wheel, such as is illustrated at 14, is especially useful for grinding tools having cemented carbide cutting edges, these tools being employed where hard metals are to be shaped or exceedingly high cutting speeds are desired. The diamond grit wheel is especially advantageous in forming these tools to the desired configuration because it cuts more rapidly than ordinary wheels, wears slowly, substantially eliminates cracking and checking of the carbide tool tip and, because of its free-cutting action, generates very little heat in the tool being ground. The precise truing of a diamond grit wheel to a desired configuration is, therefore, an important operation. As stated before, the diamond grit wheel may be crushed to shape by a vitrified silicon carbide roller and, in turn, the silicon carbide roller can be crushed to shape by a sufficiently hard steel roller. The steel roller is, in its turn, formed either by turning or grinding or any desirable combination thereof.

Thus, by forming a first roller to a predetermined configuration by ordinary machine methods and thereafter successively transferring that

configuration to other rollers having different characteristics, a final dressing action may be accomplished on a grinding wheel which is itself too hard to be dressed directly by the first roller.

It will be apparent that there could be provided more than one intermediate roller if found desirable or necessary. In each case, however, the first roll would be machine worked to have the desired configuration on its surface, and the intermediate rollers and wheel finally to be dressed would be of a substance or composition capable of being shaped by the application of pressure.

It will be understood that various modifications and arrangements in structure could be made without departing from the spirit of my invention and, accordingly, I desire to comprehend such modifications and substitutions of equivalents as may be considered to come within the scope of the appended claims.

I claim:

1. In a grinding machine; a work table; a grinding wheel movable relative to said work table; a dressing roller on said table; intermediate roller means on said table adapted to be shaped by the application of pressure thereto; means for transferring the configuration of said dressing roller to said intermediate roller means by bringing the same together under pressure and then rotating the said rollers at the same surface speeds; and means for transferring the said configuration from said intermediate roller means to said grinding wheel by bringing the same together under pressure and then rotating them at the same surface speeds.

2. In a grinding machine having a work table, a grinding wheel movable relative to said work table, a grinding wheel crush dressing roller mounted on said work table and adapted to engage said grinding wheel, a second crush dressing roller mounted on said table, means for moving said second roller on said table into pressure crush dressing engagement with said first mentioned roller, and means for effecting relative rotation of said rollers when in pressure engagement.

3. In a grinding machine having a work table, a grinding wheel movable relative to said work table, a grinding wheel crush dressing roller mounted on said work table and adapted to engage said grinding wheel, a second crush dressing roller mounted on said table, means for moving said second roller on said table into pressure crush dressing engagement with said first mentioned roller, and means for effecting relative rotation of said rollers when in pressure engagement, said first mentioned roller being mounted on said table with its working surface in planar alignment with the surface of a finished workpiece on the table.

4. In a grinding machine having a work table, a grinding wheel movable relative to said work table, a grinding wheel crush dressing roller mounted on said work table in a predetermined relationship to a work piece on said table to be ground by said grinding wheel, a second crush dressing roller for said first mentioned roller movably mounted on said table relative to said first mentioned roller, and power means for effecting relative rotation of said rollers when in engagement.

5. In a grinding machine, having a grinding wheel, and a bed, a plurality of crush dressing rollers mounted on said bed, means for effecting relative movement between said rollers to bring the respective rollers successively into engagement with one another, and means to effect en-

gagement of said grinding wheel with the one of said rollers last engaged by another of said rollers.

6. In a grinding machine, a rotatable grinding wheel mounted on said machine, a dressing wheel mounted on said machine, means for effecting pressure engagement between said grinding and dressing wheels to effect a crush dressing of said grinding wheel, a crush dressing roller also mounted on said machine, power means for rotating said roller, means for forcing said roller into pressure crush dressing engagement with said dressing wheel, and a work support associated with said machine for supporting a work piece in a predetermined relationship to said dressing wheel.

7. In a grinding machine having a rotary grinding wheel, a work table, and means for rotating said grinding wheel at grinding speed or at a slow dressing speed, a dressing wheel rotatably journaled on said work table in a predetermined position to a workpiece to be machined on said work table, a crush dressing roller rotatably journaled on said table, means for moving said roller into crush dressing pressure engagement with said dressing wheel, and power means for rotatably driving said roller when in engagement with said dressing wheel.

20 8. In a horizontal surface grinding machine having a horizontal work table, a rotatable grinding wheel mounted above said table, means for relatively reciprocating said table and wheel, a grinding wheel truing device mounted on said table with the working part of its surface located in a predetermined position relative to a work surface to be machined on a workpiece on said work table, a second truing device mounted on said work table including means for relatively moving said second truing device horizontally on said table into engagement with said first mentioned truing device so as to effect a truing operation on said first mentioned truing device, said first mentioned truing device being operable to effect a truing operation on said grinding wheel when moved into pressure engagement therewith.

30 9. In a grinding machine having a work table and a grinding wheel adjustable relative thereto, a truing device on the work table of said machine adapted to be engaged by said grinding wheel for effecting a truing thereof, and a second truing device for truing said first mentioned truing device on said work table, and means for selectively positioning said grinding wheel relative to said first mentioned truing device, and said second mentioned truing device relative to said first mentioned truing device to bring the same into operative relationship to effect a forming of said grinding wheel to the configuration of said second mentioned truing device by trans-

40 fer of the desired form through said first mentioned truing device, and means on said work table for positioning a workpiece with its surface to be ground in a predetermined relationship to the surface of engagement of said grinding wheel with said first mentioned truing device.

50 10. In a grinding machine having a work table, a rotatable grinding wheel adjustable relative to said table, a vitrified silicon carbide roller journaled on said table in position to engage said grinding wheel, a steel roller movably mounted on said table, means for moving said steel roller into pressure engagement with said silicon carbide roller, means for driving said steel roller when in engagement with said silicon car-

70 bide.

75

bide roller, and means for rotating said grinding wheel at a slow speed when in engagement with said silicon carbide roller.

11. In a grinding machine having a work table, a rotatable grinding wheel adjustable relative to said table, a vitrified silicon carbide roller journaled on said table in position to engage said grinding wheel, a steel roller movably mounted on said table, means for moving said roller into pressure engagement with said silicon carbide roller, means for driving said steel roller when in engagement with said silicon carbide roller, means for rotating said grinding wheel at a slow speed when in engagement with said silicon carbide roller, and means for mounting a workpiece on said work table with its surface to be ground located in a predetermined relationship to said silicon carbide roller, whereby relative reciprocation of said work table and grinding wheel will present said grinding wheel selectively to said workpiece or to said vitrified silicon carbide roller.

12. In a grinding machine; a grinding wheel; means for driving said wheel at grinding speed or at crushing speed; a work table reciprocable relative to said wheel; a first dressing roller adapted for being shaped by pressure rotatably mounted on said table; a second dressing roller rotatably and reciprocably mounted on said table; means for moving said second roller into pressure engagement with said first roller and for driving said second roller in rotation to form said first roller to desired shape; and means for moving said wheel and first roller into pressure engagement and for driving said wheel at crushing speed for shaping said wheel.

13. In a grinding machine having a grinding wheel and a worktable, a first crush dressing roller on said table adapted to crush form said wheel by pressure engagement therewith, a second crush dressing roller on said table adapted to crush form said first roller by pressure engagement therewith, means for relatively moving said rollers on said table to bring them into pressure contact to crush form the first thereof, and power means for driving said rollers when in crushing engagement.

14. In a grinding machine having a work supporting table and a rotatable grinding wheel, a dressing wheel mounted on said table operable to dress said grinding wheel upon pressure engagement therewith, a crush dressing roller movably mounted on said table, power means for rotating said roller, means for forcing said roller into pressure crush dressing engagement with said dressing wheel, and means for supporting a workpiece on said table in a predetermined relationship to said

dressing wheel, said grinding wheel and table being relatively adjustable to bring said grinding wheel into working relationship with said workpiece or into position for pressure engagement of said grinding wheel with said dressing wheel.

15. In a grinding machine having a grinding wheel and a work table, a first crush dressing roller having a configuration complementary to that of the grinding wheel and adapted for forming said wheel by pressure engagement therewith, said first roller being mounted on said table in a predetermined position relative to a surface to be ground on a workpiece on said table, a second crush dressing roller also mounted on said table and having a configuration complementary to that of said first roller and adapted for shaping said first roller by pressure engagement therewith, means for driving said grinding wheel and first roller at equal surface speeds while in pressure engagement to shape said wheel by said first roller, and means for bringing said first and second rollers into crush dressing engagement and for driving said rollers at equal surface speeds.

16. In a grinding machine having a grinding wheel and a work table, a first crush dressing roller mounted on said table having a configuration complementary to that of the grinding wheel and located in a predetermined position relative to a surface to be ground on a workpiece on said table, a second crush dressing roller having a configuration complementary to that of said first roller and adapted to crush form said first roller by pressure contact therewith, said first roller being adapted for crush forming said grinding wheel by pressure contact therewith, means for driving said grinding wheel and said first roller at equal surface speeds, means for bringing said first and second rollers into crush dressing engagement, and means for driving said rollers at equal surface speeds, said grinding wheel and table being relatively adjustable for selectively positioning said grinding wheel in operative relationship with said first roller or with a workpiece in said machine.
